HAIRSPRING OVERCOIL RAISING TOOL

William Ogle Bennett, Jr., Lancaster Township,
Lancaster County, Pa., assignor to Hamilton
Watch Company, Lancaster, Pa.

Application October 16, 1944, Serial No. 558,815

4 Claims. (Cl. 153—21)

1

This invention relates to a tool for raising the overcoil on hairsprings of the finer type watches. In order to assure the isochronal quality of a watch it is necessary that the hairspring be made to expand and contract equally in all directions. It has been found that proper overcoiling of the hairspring allows this expansion and contraction to be more nearly concentric than if the outer end of the hairspring is secured to the cock in the same plane, and consequently the isochronism is better. This makes it necessary to raise the outermost coil of the hairspring above the plane of the main section of the hairspring and to curve said raised coil inward in a certain predetermined curve. To maintain uniformity in hairsprings it is highly desirable that the raising be done by means of a machine or tool which eliminates any human element. The tool forming the subject of this invention is utilized for raising the last coil of the hairspring above the plane of the remainder of the spring.

The object of the present invention is to provide a tool which raises the outermost coil of the hairspring to a position above the plane of the main body of the spring.

A further object of the present invention is to provide a tool by means of which the outermost coil of a hairspring is raised by a predetermined amount so that where watches are produced in quantity, the overcoil will be raised exactly the same amount above each and every hairspring.

A further object of the present invention is to provide a tool for producing exactly the same bends in a hairspring to raise an overcoil.

A further object of the invention is to provide means by which the bends made in the last coil of the hairspring may be regulated so that the overcoil may be raised a predetermined amount.

It is a still further object of the present invention to provide means for supporting a hairspring while on the balance and for raising the overcoil while the hairspring remains attached to the balance.

It is a still further object of the present invention to provide means by which the outermost coil of the hairspring is firmly held and the raising accomplished in a single operation.

It is a still further object to raise the outermost coil of the hairspring and maintain the raised portion in a plane parallel to the main body of the spring.

With the foregoing and other objects in view, the invention resides in the novel arrangement and combination of parts and in the details of construction hereinafter described and claimed,

2

it being understood that changes in the precise embodiment of the invention herein described may be made within the scope of what is claimed without departing from the spirit of the invention.

The invention is illustrated in the accompanying drawing in which:

Fig. 1 is a top plan view;

Fig. 2 is a section on line 2—2 of Fig. 1;

Fig. 3 is a detailed view showing the last coil of the hairspring in the position just previous to making the bend;

Fig. 4 is a detailed view showing the last coil of the hairspring in the position just after making the bend;

Fig. 5 is an enlarged view of the hairspring showing the raised overcoil.

The tool is formed with a base 1 having mounted at one end a balance holder 2 secured by screws to the base 1 and formed with a semi-circular groove 5 to receive the balance 6 of a hairspring 7 having an outermost coil 8.

A pair of supporting members 9 and 10 are mounted on the base 1. Member 9 is securely held to the base by screw 28 passing through a hole in said member, while member 10 is slightly movable through the screw 29 passing through a slot in said member. These supporting members 9 and 10 respectively support a pair of slides 11 and 12 which are also held by screws 28 and 29 passing through slots permitting longitudinal movement of the members 11 and 12 on the supporting members 9 and 10. A handle member 13 controls the sliding action of the slides 11 and 12 through links 14 and 15 under manual operation. The ends of the supporting members 9 and 10 farthest from the link member 15 are formed with curved surfaces 16 and 17 which receive the outermost coil of the hairspring 8 and have mounted respectively thereon holding blocks 18 and 19 serving to hold the coil 8 in desired position.

The forward edges of the slide members 11 and 12 are formed with tongues 20 and 21, the under side of which is curved to fit the surfaces 16 and 17 and the upper side is curved to fit beneath the projecting edges 22 and 23 of the holding blocks 18 and 19 respectively. The slide members 11 and 12 are mounted for longitudinal sliding motion on the supporting members 9 and 10 by means of pins 24 in said supporting blocks passing through slots 25 in the sliding members while spring members 26 and 27 control the sliding motion of the two sliding mem-

bers 11 and 12 relative to each other through the adjustment of the spring tension by the screws 28 and 29 threaded into base 1 and passing through slots 28' and 29' respectively of the sliding members 9 and 10 and slots 28'' and 29'' respectively of the members 11 and 12. These slots both in the members 9 and 10 and 11 and 12 give a sufficient freedom of movement to the members to permit both a sliding movement in a longitudinal direction and a slight lateral movement. A spring 3 carried between members 9 and 10 and housed within a groove 4 in member 9, normally holds said members in spaced relationship. A pair of pins 30 mounted in the supporting block 10 engage cams 31 and when forward movement of the slide member 12 engages the pins 24 and imparts further movement to the supporting member 10, said pins 30 cause a lateral motion of the supporting member 10 and its supporting slide 12 to bring the supporting members together while they move longitudinally to thus produce a permanent bend in the top coil 8 of the spring held in bending position.

Threaded into the rear portion of the base is a limiting screw 32 having an elongated cylindrical portion 33 engaging a downwardly projecting pin 34 to limit the rearward motion of the supporting member 10. The pin 34 is affixed to the supporting member 10 and projects downwardly into the opening 35 of the base 1. A second limiting screw 36 threaded into the forward portion of the base engages a pin 37 projecting downward from supporting member 10 into the opening 38 of the base 1. This screw 36 limits the forward motion of the member 12 and regulates the distance which the outer coil of the hairspring is raised above the hairspring.

In operation, a hairspring together with its accompanying balance is placed in the balance holder 2 with the spring drawn out and placed in a position shown in Fig. 2 so that the outer coil 8 passes below and is held beneath the overhanging end 22 of the block 18, the curved portion of the spring snugly fitting the curved surface of the ends 16 and 17. The end 16 is formed with a curved cutaway portion 39 while the end of the opposing slide is curved at 40 to produce the desired curve in the hairspring overcoil. The curved surface 41 of the cam 31 is formed with extreme accuracy and guides the pins 30 so that the movement of the supporting member 10 and its accompanying slide 12 produces just the exact curve necessary to make the overcoil.

The outer coil of the hairspring being fixed in a position shown in Fig. 2, the handle 13 is pushed forward, moving the slide member 11 into spring contacting position which is followed by movement of slide member 12 into a light spring contacting position. Continued movement of the lever causes the pin 24 to contact the end of the slot 25 and impart its sliding motion to the supporting member 10. Forward movement of the supporting member 10 causes the pins 30 to ride against the curved surface of the cams 31, moving the supporting member 10 and its accompanying slide 12 laterally as it moves forwardly forcing the spring against the cut out portion 39 to produce the bends 42 shown in Fig. 5. The handle being released, the spring returns the slide to starting position and the coil is manually removed from the holding overhanging end 22 and allowed to return into the balance, the outer coil of the hairspring having a permanent deformation to produce a raised section above that of the main body of the spring.

With an instrument of this type it is possible to get uniformity in the raising of the overcoil. Heretofore, overcoils have been made entirely by hand and depended entirely on the skill of the operator. With this device it is possible for any one to raise a perfectly level overcoil and also to have uniformity in a great number of hairsprings.

What is claimed is:

1. A tool for raising an overcoil on watch hairsprings comprising a base, a balance wheel and hairspring support carried at one end of said base, a stationary slide supporting member, a movable slide supporting member adjacent to said stationary supporting member, a spring normally separating said members, each of said supporting members being narrowed at one end, said narrowed portions being curved on their top surface to receive the outermost coil of said hairspring, slides mounted for limited sliding movement on each of said supporting members, an adjustable spring to regulate the sliding contact pressure between each of said slides and its supporting member, a pin carried on each of said supporting members receivable in a slot in each of said slides to prevent lateral movement of the slides relative to said supporting members, a link connecting said slides at one end, the other end of said slides being formed with tongue portions curved to fit the curved narrowed ends of the supporting members and to engage the outermost coil of said hairspring, a pair of blocks formed with an overhanging end mounted on the narrowed ends of the supporting members to confine the outermost coil of the hairspring in desired position, a handle member connected to said link to move the slides upon movement of said handle, a pair of cam followers carried on the sliding supporting member, a pair of cams mounted on said base and engaging said cam followers to impart lateral movement to said sliding supporting member and its slide, whereby upon movement of said handle the slides move forward in order, dependent upon spring tension between the slides and their supporting members, within their limits, further movement of one of said slides moving its accompanying supporting member both longitudinally and laterally to bend said outermost coil of the hairspring to its desired shape.

2. A tool for raising an overcoil on watch hairsprings, comprising a base, means for holding a hairspring and balance assembly mounted at one end of said base, a pair of sliding members mounted for manually controlled sliding movement carried on said base, one of said members moving longitudinally and the other of said members moving both longitudinally and laterally of said base; means for holding the outermost coil of said hairspring in predetermined position and in the path of said sliding members, means for selectively controlling the movement of said sliding members to bring the longitudinal sliding member into clamping engagement with the outermost coil of the hairspring and to engage said clamped coil with said second sliding member to bend said coil into predetermined shape.

3. A tool for raising the overcoil of a hairspring comprising a base, means carried by said base for supporting a hairspring and balance assembly means carried by said base and adjacent said supporting means engaging predetermined lengths of the edges of the outer coil of the hairspring adjacent the bending points, said means maintaining said outer coil in its original curvature, and means slidably mounted on said base 75 for bending a portion of said outer coil into a

plane parallel to and above the body of the hairspring while maintaining the original curvature of said outer coil.

4. A tool for raising an overcoil on watch hairsprings comprising a base, means for supporting a hairspring and balance assembly, a pair of sliding members mounted on said base for manually controlled sliding movement, means located in the path of movement of said sliding members for cooperating with one of said sliding members to clamp the outermost coil of the hairspring in a predetermined position and means cooperating with the other of said sliding members to bend the outermost coil of the hairspring upon longi-

tudinal and lateral motion of said second of said sliding members.
